HENRY R. ATWOOD, OF CHELSEA, MASSACHUSETTS.

Letters Patent No. 86,051, dated January 19, 1869.

IMPROVEMENT IN REEFING SAILS.

The Schedule referred to in these Letters Patent and making part of the same.

To all persons to whom these presents may come:

Be it known that I, HENRY R. ATWOOD, of Chelsea, of the county of Suffolk, and State of Massachusetts, have invented a new and useful Improvement in Reefing a Mainsail, or other sail of like character of a navigable vessel; and I do hereby declare the same to be fully described in the following specification, and represented in the accompanying drawings, of which—

Figure 1 is a front elevation of the mast, boom, gaff, and mainsail of a schooner, as provided with my invention.

Figure 2 is a transverse section of the gaff, its rail, and one of the travellers thereof, to be hereinafter described.

In such drawings—

A denotes the mast;
B, the boom;
C, the gaff; and
D, the mainsail.

In carrying out my improvement, I form the sail with its outer edge, *a d*, equal or about equal in length to the diagonal *b d*, along which I secure a strengthening-stay or rope, *e*.

To the under side of the gaff I affix a rail, *f*, like an **H** or **T**-rail of a railway.

This rail supports a series of travellers, *g g g*, each being very like in form the traveller of a ring-spinning frame. They are secured, at equal distances apart, to the head of the sail.

The sail is to be applied to the mast and boom in the ordinary manner, and the gaff and boom are to be furnished with the usual ropes and appliances for operating them.

In further carrying out my invention, I combine, with the outer leach of the sail, one or more ropes, *h*, *i*, for reefing the triangular part *a b d*, by drawing the outer leach, *a d*, up to the diagonal, *b d*.

The upper of the said ropes, fastened to the upper corner of the sail, is carried through the series of travellers *g g g*, and thence down to the deck.

The next of said ropes is fastened to the outer leach. From thence it runs, parallel to the head of the sail, to an eye or ring, *r*, fixed to the stay-rope *e*, thence down along the stay-rope to and through a ring at the lower outer corner of the sail.

There may be any suitable number of such ropes *i* applied to the sail in like manner.

I also apply to the said sail, on the head thereof, and the gaff, a rope, *k*, for drawing the leach-rope *a d* away from the diagonal *b d*, so as to unreef the part *a b d*. This rope *k* is led up through the gaff, and thence to and through a guide or block, *l*, affixed to the mast, and thence down to the deck.

I am aware that the triangular part *a b d* has been reefed by dropping the gaff down into a vertical position, or against the mast, so as to carry to the leeward of the rest of the sail, the part to be reefed, and that for the purpose of supporting the remainder of the sail, a rope has been affixed to and diagonally across the sail. I therefore make no claim thereto.

I claim the combination and arrangement of the rail and travellers with the gaff and the sail, and lines or devices for reefing and unreefing the outer triangle or part *a b d* of the sail, in manner substantially as set forth; that is, by drawing the outer leach up to the diagonal rope, or away therefrom, as specified, the said leach having a length to correspond with that of such diagonal; the whole being substantially as explained.

H. R. ATWOOD.
